UNITED STATES PATENT OFFICE

PHILIP BONAVENTURA, OF PHILADELPHIA, PENNSYLVANIA

DISPENSING RECEPTACLE FOR CIGARS AND CIGARETTES

Application filed July 15, 1929. Serial No. 378,294.

My invention relates to a dispensing receptacle for cigars and cigarettes, that is to say, to a device adapted to receive and contain a supply of cigars and cigarettes, and to dispense the same alternatively, according to the desire of the operator.

The principal object of my present invention is to provide, in a unitary structure, a receptacle for cigars and cigarettes, which is adapted to dispense one cigar or cigarette each time the apparatus is actuated.

A further object of my invention is to provide, in such a device, means for delivering the cigar or cigarette, as the case may be, to the same delivery position in each instance.

A further object of my invention is to provide, in a device of the character aforesaid, a lighter adapted to be automatically opened and lighted as a cigar or cigarette is obtained from its respective magazine.

The nature and characteristic features of my invention will be more readily understood from the following description, taken in connection with the accompanying drawings forming part hereof, in which:

Figure 1 is a perspective view of a cigar and cigarette dispensing receptacle, embodying the main features of my present invention;

Fig. 2 is a transverse, vertical, central section thereof;

Fig. 3 is a vertical section taken approximately on the line 3—3 of Fig. 2;

Fig. 4 is a vertical section taken approximately on the line 4—4 of Fig. 2;

Fig. 5 is a top or plan view of the receptacle with the lid or cover partly broken away;

Fig. 6 is a fragmentary, sectional, detail view illustrating the positions of the delivery members when the same are depressed for the purpose of obtaining a cigar from the cigar magazine;

Fig. 7 is a similar view, illustrating the positions of the delivery members when the

cigarette delivery member is depressed for the purpose of obtaining a cigarette from its magazine; and

Fig. 8 is a sectional detail view illustrating portions of the mechanism for operating the lighter.

It will, of course, be understood that the drawings and descriptions herein contained are illustrative merely, and that various modifications and changes may be made in the structure without departing from the spirit of my invention.

Referring to the drawings, in the particular embodiment of my invention therein shown, 10 is a casing or housing, which may be made of sheet metal, of any preferred shape. Centrally disposed on the inner faces of the opposite side walls of the casing are guide strips 11.

The guide strips 11 serve as a means for slidably mounting a depressible cigar delivery member 12, the upper portion of which is provided with a longitudinal depression 13. There is also provided a depressible cigarette delivery member 14, which is slidably mounted within the cigar delivery member 12. The upper portion of the cigarette delivery member is also provided with a depression 15, which normally forms a continuation of the depression 13 in the top of the cigar delivery member.

The cigar delivery member is provided with portions 16, which extend over the body portion of the cigarette delivery member, this arrangement being provided so that the cigarette delivery member may be depressed independently of the cigar delivery member, but on the other hand, when the cigar delivery member is depressed, the cigarette delivery member will be carried with it.

The cigar delivery member is provided with a bracket 17, which slidably engages an upright post 18, the lower end of which is secured to a portion of the casing. A coil

spring 19 is mounted upon the post 18, and has its lower end bearing against the portion of the casing to which the post is secured, and its upper end bearing against the bracket 17. By this arrangement, the spring 19 pushes the cigar delivery member upwardly, and normally maintains the same in the position shown in the drawings, in Figs. 1 to 5 thereof.

10 The cigar delivery member is also provided with another bracket 20, in which the lower end of a rod 21 is threaded. The upper end of the rod 21 is provided with a finger button 22, whereby the cigar delivery member may be manually depressed against the tension of the spring 19.

15 In the interior of the cigarette delivery member, there is provided a rod 23, the upper end of which is secured to the upper portion of the cigarette delivery member. The lower end of the rod 23 telescopes in a tube 24. The lower end of the tube 24 is secured to a rigid portion of the casing.

20 A coil spring 25 surrounds the tube 24 and rod 23. The lower end of spring 25 bears against the portion of the casing to which the tube 24 is secured, and the upper end of said spring bears against the upper portion of the cigarette delivery member. The 25 spring 25 pushes the cigarette delivery member upwardly, and normally holds the same in the position shown in the drawings, in Figs. 1 to 5 thereof.

25 The cigarette delivery member is also provided with a bracket 26, in which the lower end of a rod 27 is threaded. The upper end of the rod 27 is provided with a finger button 28 for manually depressing the cigarette delivery member against the tension of the spring 25.

30 The cigar and cigarette delivery members are positioned in the central portion of the casing by means of the guide strips 11, hereinbefore described. A cigar magazine 29 is 35 provided on one side of the delivery members, and a cigarette magazine 30 is provided on the other side thereof.

35 The cigar magazine is provided with an inclined floor 31. A vertical wall 32 extends across the side of the cigarette magazine adjacent the delivery members, the lower end of this wall terminating a sufficient distance above the bottom of the cigar magazine to permit but one cigar to pass when the cigar and cigarette delivery members are simultaneously in the lowermost position.

40 The bottom of the cigarette magazine is likewise provided with an inclined floor 33, and on the side of the cigarette magazine adjacent the delivery members there is provided a wall 34, the upper portion of which is inclined away from the delivery members, and the lower portion of which is curved around, as at 35, a sufficient distance from the inclined floor 33 of the cigarette maga-

zine to cause the cigarettes to be arranged in a single row prior to their being fed to the delivery member.

45 At the lower end of the cigarette magazine there is provided a slidable member 36, the upper portion of which slopes toward the delivery members, as at 37 on one side, and away from the delivery members, as at 38 on the other side, for a purpose to be presently explained.

50 The slidable member 36 is normally in the depressed position. To insure the return thereof to the depressed position, there is provided a spring 57, the upper end of which is connected to a post 58 projecting from the slidable member, and the lower end of which is connected to a post 59 extending from a portion of the casing.

55 A lever 40 is mounted below the slidable member 36, being pivoted as at 41, in a bracket carried by a portion of the housing. One end of the lever 40 bears against the under side of the slidable member 36, and the other end thereof has a projecting portion 42 which is adapted to be encountered by the lower end of the cigarette delivery member 14 when the same passes to its lowermost position, the arrangement being such that when the cigarette delivery member is depressed independently of the cigar delivery member, the slidable member 36 will be elevated, for a purpose to be presently explained.

60 A cigar lighter 43 of the well known pocket type is also mounted in the casing, and the same is so arranged that when the lid of the casing is opened through the actuation of a button, the lighter will become ignited. Devices of this character are in common, everyday use, and as the specific 65 construction forms no part of the present invention, the same is not shown or described in detail.

65 The upper hinged cover portion of the cigar lighter 43 projects through the lid of the casing. The button of the cigar lighter is adapted to be engaged by a corrugated wheel 44, which is mounted on one end of a horizontal shaft 45. The shaft 45 is journaled in suitable brackets carried by the 70 casing.

75 The other end of the shaft 45 is provided with a ratchet wheel 46, which is engaged by the free end of a leaf spring 47. The other end of the leaf spring 47 is secured to the bracket 26, to which the lower end of the actuating rod 27 of the cigarette delivery member is also secured.

80 The top of the casing is provided with a lid portion 48, hinged as at 49 to the body portion of the casing, and normally held closed by means of a spring latch 50. By raising the lid 48 access may be had to the magazine for replenishing the supply of 85 cigars and cigarettes.

The bottom or base portion 51 of the casing is also preferably hinged, as at 52, to the body portion of the casing, whereby access may be had to the internal mechanism.

5 The operation of the device may now be explained. The supply of cigars and cigarettes contained in the respective magazines will be impelled by the sloping bottom portions of the magazines toward the centrally arranged delivery members.

10 When it is desired to obtain a cigarette, the finger button 28 is depressed, whereby, through the rod 27, the cigarette delivery member 14 will be depressed to its lowermost position, against the tension of the spring 25. As the bottom of the cigarette delivery member approaches its lowermost position, the same will encounter the projecting end 42 of the lever 40, depressing 15 the same and causing the other end of the lever 40 to elevate the slide member 36 against the tension of the spring 37.

15 When the parts are actuated as above set forth the cigarette which lies immediately adjacent the vertical wall 53, in the lower end of the cigarette magazine, will be pushed upwardly, and by reason of the sloping portion 37 of the top of the slide member, the cigarette will roll inwardly and 20 lodge within the depressed portion 15 at the top of the cigarette delivery member 14 which has been brought to the proper position by the depression thereof.

25 The finger button 28 being now released, the spring 25 will cause the cigarette delivery member to move upwardly until it reaches its uppermost position, whereupon the cigarette will lie approximately flush with the top surface of the lid of the casing, whence it may be removed by the user.

30 As the cigarette delivery member thus passes upwardly, the free end of the spring 47 will encounter the ratchet wheel 46, rotating the same for one tooth, thus bringing 35 one of the projections of the corrugated wheel 44 in contact with the button of the cigar lighter. In this manner, the cover of the cigar lighter will be released and the lighter caused to function in the customary manner.

35 Should, however, a cigar be desired, the finger button 22 is depressed, and thereby, through the rod 21 the cigar delivery member will be depressed against the tension of the spring 19.

40 It may here be noted that by reason of the engagement of the portions 16 of the cigar delivery member overlapping the cigarette delivery member, the cigarette delivery member will be caused to be depressed with the cigar delivery member, so that there will be no break in the continuity of the upper surface of the delivery members.

45 However, the cigar delivery member is limited in its downward movement, so that

as the same reaches its lowermost position, the depressed top portion thereof will be brought to a position whereby a cigar will be permitted to roll from the magazine on to the same.

50 Upon the release of the finger button 28, the cigar delivery member will be impelled upwardly by means of the spring 19, until the upper portion thereof causes the cigar to be brought approximately flush with the 55 top surface of the lid.

55 It may here be noted that whenever the cigar delivery member is depressed as aforesaid, the cigarette delivery member will be carried downwardly therewith, but to a less extent than when the cigarette delivery member alone is depressed.

60 It may also be noted that when the mechanism above described is actuated for the purpose of obtaining a cigar from the cigar delivery member, the spring arm 47 which is carried by the cigarette delivery member will actuate the lighter mechanism, in its movement with the cigarette delivery member so that the lighter will always function 65 whenever a cigar or a cigarette is obtained from its magazine.

I claim:

1. A device of the character described comprising a casing, a vertically movable 95 delivery member mounted in said casing, means for actuating said delivery member, the casing having a cigar magazine arranged on one side of the delivery member and a cigarette magazine arranged on the other 100 side thereof, and means for selectively feeding a cigar or a cigarette from the respective magazines to the delivery member.

2. A device of the character described comprising a casing, a delivery member 105 movably mounted in said casing, means for actuating said delivery member, the casing having a cigar magazine and an independent cigarette magazine, the lower portion of the cigar magazine having an opening 110 through which the cigars are separately fed to the delivery member, said opening being normally closed by said delivery member, and means arranged at the bottom of the cigarette magazine adapted to be actuated by a portion of the delivery member 115 to cause the cigarettes to be separately fed thereto.

3. A device of the character described comprising a casing, a delivery member 120 movably mounted in said casing, means for actuating said delivery member, the casing having a cigar magazine arranged on one side of the delivery member and a cigarette magazine arranged on the other side thereof, the lower portion of the cigar magazine having an opening through which the cigars are separately fed to the delivery member, said opening being normally closed by said 125 delivery member, and means arranged at 130

the bottom of the cigarette magazine adapted to be actuated by a portion of the delivery member to cause the cigarettes to be separately fed thereto.

5. A device of the character described comprising a casing, a delivery member movably mounted in said casing, means for actuating said delivery member, the casing having a cigar magazine arranged on one 10 side of the delivery member and a cigarette magazine arranged on the other side thereof, the lower portion of the cigar magazine having an opening through which the cigars are separately fed to the delivery member, said opening being normally closed by said delivery member, and means arranged at the bottom of the cigarette magazine adapted to be actuated by a portion of the delivery member to cause the cigarettes to be separately fed thereto, said last mentioned means comprising a movable member having its 15 upper portion shaped to cause one of the cigarettes to be impelled to the delivery member and to restrain the passage of the other cigarettes within the magazine, and a lever having one arm engaging the lower portion of said movable member and having its other arm adapted to be engaged by a portion of the delivery member.

30. A device of the character described comprising a casing, a two-part delivery member movably mounted in said casing, one part of said delivery member being movably arranged with respect to the other, means for actuating one part of said delivery member independently of the other, means for simultaneously actuating both parts of said delivery member, the casing having a cigar magazine arranged on one 35 side of the delivery member and a cigarette magazine arranged on the other side thereof, and means for selectively feeding a cigar or a cigarette from the respective magazines to the delivery member according to whether the independently operable part of the delivery member is actuated or both parts of said delivery member are simultaneously actuated.

50. A device of the character described comprising a casing, a two-part delivery member movably mounted in said casing, one part of said delivery member being movably arranged with respect to the other, means for actuating one part of said delivery member independently of the other, means for simultaneously actuating both parts of said delivery member, the casing having a cigar magazine arranged on one 55 side of the delivery member and a cigarette magazine arranged on the other side thereof, the lower portion of the cigar magazine having an opening through which the cigars are separately fed to the delivery member, and means arranged at the bottom of the cigarette magazine adapted to be actuated

by a portion of the delivery member to cause the cigarettes to be separately fed thereto.

7. A device of the character described comprising a casing, a two-part delivery member movably mounted in said casing, 70 one part of said delivery member being movably arranged with respect to the other, means for actuating one part of said delivery member independently of the other, means for simultaneously actuating both 75 parts of said delivery member, the casing having a cigar magazine arranged on one side of the delivery member and a cigarette magazine arranged on the other side thereof, the lower portion of the cigar magazine 80 having an opening through which the cigars are separately fed to the delivery member, said opening being normally closed by said delivery member, and means arranged at the bottom of the cigarette magazine adapted 85 to be actuated by the independently operable part of the delivery member to cause the cigarettes to be separately fed thereto.

8. A device of the character described comprising a casing, a two-part delivery 90 member movably mounted in said casing, one part of said delivery member being movably arranged with respect to the other, means for actuating one part of said delivery member independently of the other, 95 means for simultaneously actuating both parts of said delivery member, the casing having a cigar magazine arranged on one side of the delivery member and a cigarette magazine arranged on the other side 100 thereof, the lower portion of the cigar magazine having an opening through which the cigars are separately fed to the delivery member, said opening being normally closed by said delivery member, and means arranged at the bottom of the cigarette magazine 105 adapted to be actuated by the independently operable part of the delivery member to cause the cigarettes to be separately fed thereto, said last mentioned means comprising a movable member having its upper portion shaped to cause one of the cigarettes 110 to be impelled to the delivery member and to restrain the passage of the other cigarettes within the magazine, and a lever having one arm engaging the lower portion of said movable member and having its other arm adapted to be engaged by the lower portion of the independently operable part 115 of the delivery member.

9. A device of the character described comprising a casing, a cigarette delivery member movably mounted in said casing, a cigarette magazine arranged on one side of said delivery member, and means arranged 120 at the bottom of the cigarette magazine adapted to be actuated by the delivery member to cause the cigarettes to be separately fed thereto, said last mentioned means comprising a movable member having its upper 125 portion shaped to cause one of the cigarettes to be impelled to the delivery member and to restrain the passage of the other cigarettes within the magazine, and a lever having one arm engaging the lower portion of said movable member and having its other arm adapted to be engaged by the lower portion of the independently operable part 130 of the delivery member.

portion shaped to cause one of the cigarettes to be impelled to the delivery member and to restrain the passage of the other cigarettes within the magazine, and a lever having one 5 arm engaging the lower portion of said movable member and having its other arm adapted to be engaged by the lower portion of the delivery member.

In testimony whereof I have hereunto 10 signed by name.

PHILIP BONAVENTURA.
